REFRIGERATOR CAR CONSTRUCTION

Earl R. Swanson, Chicago, Ill., assignor to Standard Railway Devices Company, a corporation of Delaware

Application January 25, 1940, Serial No. 315,465

7 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling means and a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment thereby cooling the lading, and finally to the cooling means from where the cycle is repeated.

There are several types of refrigerant containers commonly used in a car of this type. The containers may be foraminous when fresh water ice or eutectic ice is used, or partly foraminous and partly imperforate when it is desired to retain all, or part, of the salt and melted refrigerant. Wholly imperforate containers, or containers substantially imperforate with a relatively small number of small holes, may be provided when it is desired to retain the melted refrigerant or the brine which is formed by the melting of the refrigerant. Provision is thus provided for the overflow of refrigerant from the containers. A liquid is also formed by the condensation of moisture from the circulating air upon the cold surface of the refrigerant container. This liquid from either of the above-mentioned sources is drained downwardly through the side wall flues to the lower part of the car from which it must be disposed of.

It is an object of the invention to dispose of the liquid draining through the side wall flue and to prevent the splashing of said liquid upwardly into the lading space, where it would cause considerable damage to the lading.

Another object of the invention is to provide a deflecting means which functions to provide a smooth path for the flow of circulating air from the side wall flue into the space under the floor rack, thereby increasing the refrigerating

efficiency by accelerating the flow of the refrigerated air.

A further object of the invention is to provide a means to receive the liquid from the side wall flue, which means may be easily dismantled and cleaned. Ice, which is commonly used in refrigerator cars, often carries with it small particles of foreign matter which accompany the liquid down the side wall flue and provisions must be made for removing these foreign particles from the interior of the car.

Other objects and advantages of my invention will be apparent from the following detailed description by referring to the accompanying drawings.

In the drawings:

Fig. 1 is a partial transverse section of a refrigerator car embodying my invention.

Fig. 2 is an enlarged view of a portion of Fig. 1 showing the liquid receiving means.

Fig. 3 shows a modified construction of the part of the car shown in Fig. 2.

Fig. 4 is similar to Fig. 2 with the floor rack and perforated plate swung upwardly for cleaning purposes.

Fig. 5 is a section on line 5—5 of Fig. 2.

Figs. 6 and 7 are views similar to Fig. 2 showing modified constructions.

Fig. 8 is a modified design of part of the car shown in Fig. 5.

The general parts of the refrigerator car shown are insulated roof 2; side wall 3; floor 4; hatch 5; refrigerant container 6; side wall flue 7; foraminous floor rack 8 and space 9 between rack 8 and floor 4. A refrigerant container 6 is positioned directly below the roof 2 and adjacent the side wall 3. A drip pan 12 is provided below the container 6 and a partition 14 is secured in an upstanding position at the edge of the drip pan 12. The drip pan 12 and partition 14 cooperate with the roof 2 and side wall 3 to form an enclosing structure 11 around the container 6, an air inlet opening 15 being provided by spacing the partition 14 from the roof 2. An air discharge opening 17 which leads to the flue 7 is formed by spacing the drip pan 12 from the wall 3. Cars of this type commonly have a row of refrigerant containers 6 near each side wall 3 and spaced apart at the center of the car. The partitions 14 are also spaced apart to form a duct 16 which communicates between the lading compartment 18 and openings 15.

Air circulation is as follows: Air in the lading compartment 18 is warmed by contact with the lading and rises through the duct 16 to enter

the enclosing structures 11 through the air inlet openings 15. The air is cooled by contact with the refrigerant containers 6 and falls by reason of its greater density through the discharge openings 17 and flues 7 to the space 9 whence it rises through the rack 8 to the lading compartment 18. The containers 6 may be provided with apertures 19 for overflow of liquid refrigerant.

The side wall construction of the car shown in Fig. 1 comprises inner 24 and outer 25 side plates; inner 27 and outer 28 sills; outer posts 30 extending between and secured to the outer plate 25 and outer sill 28 and inner posts 31 extending between and secured to the inner plate 24 and inner sill 27. A wooden floor 33 extends between the inner side sills 27 on opposite sides of the car and is supported adjacent the sills by Z-shaped members 35 secured to the inwardly projecting legs 36 of the sills 27. A metal covering 38 may be provided for the wooden floor 33.

A trough 42 is formed substantially below the side wall flue 7 by the Z-shaped member 43, which trough 42 is defined by the inner side sill 27 and Z-shaped member 43. A plate 45, preferably metallic, is arranged to substantially cover the trough 42 and has relatively small apertures 46 therein so that any liquid draining from the flue 7 drains through the apertures 46 in the plate 45 and into the trough 42. The relatively small apertures 46 permit the liquid from the flue 7 to drain into the trough 42 but prevent any substantial amount of liquid splashing from the trough 42 through the apertures 46 and into the lading space 18. The plate 45 is disposed concave upwardly to direct the circulating air in a smooth path into the space 9 under the floor rack 8 and has its lowest part 48 disposed over the trough 42 so that liquid draining onto the plate 45 naturally flows to the lowest part 48 thereof and then drains into the trough 42. The upper, outer edge 50 of the plate 45 is bent and rebent; the rebent part 52 being disposed in a pocket 53 formed between the retaining member 55 and the inner sill 27. This arrangement forms a floating hinge 56 about which the plate 45 may be swung upwardly. The opposite edges 58 of the plate 45 preferably rests upon the Z-shaped member 43 and is held in this position by stringers 60 of the floor rack 8 resting thereon.

When it is desired to clean the plate 45 or the trough 42, the floor rack 8 is swung upwardly against the side wall lining 63, as shown in Fig. 4, and the plate 45 may then also be swung upwardly as also shown in Fig. 4 for cleaning purposes.

A drain 66, which may be water sealed if desired, is provided through the floor 4 of the car at any location desired, preferably at a substantial distance from the trough 42. A conduit 67 is provided above the floor 4 of the car leading from the trough 42 to the drain 66 as shown in Fig. 1. Fig. 5 shows a cross section of the conduit 67 shown in Fig. 1, which conduit consists of an open channel 69 having the upper edges 70 thereof bent inwardly and downwardly to prevent liquid splashing from the conduit 67 through the floor rack 8 and into the lading compartment 18.

In the modification shown in Fig. 8 the conduit 73 is completely enclosed to prevent splashing into the lading compartment 18.

Fig. 6 shows a modification in which the plate 75 is unattached to the car structure but one edge 76 thereof rests upon the Z-shaped member 78 and the plate 75 is held in this position by the

finger 79 secured to the floor rack stringer 81 and projecting therefrom.

Fig. 7 shows a modification in which the plate 85 is attached by means of a floating hinge 86 as described in reference to Fig. 1. An angle shaped member 88 is provided in place of the Z-shaped member 43 of Fig. 1 and the inner, lower edge 89 of the plate 85 is formed with a downwardly facing channel 91 arranged to overlie the upstanding leg 92 of the angle 88 and thereby form a water-tight seal. The edge 89 of the plate 85 may have a horizontal flange 94 arranged to underlie the floor rack stringers 95 and thus be held rigidly in position.

Fig. 3 shows a plate 100 similar to that described in reference to Fig. 6, adapted to a car in which the side wall flue 7 is formed between the lining 101 of the car and a metallic sheet 103 having a panel 104 pressed therein. In this arrangement the perforated plate 100 is not directly below the flue 7 but liquid drained through the flue 7 is directed upon the perforated plate 100 by the sloping margin 106 of the panel 104.

In order to prevent liquid retained in the trough 42 from surging lengthwise of the car, baffle plates 110 may be provided depending in a substantially vertical plane from the perforated plate 45, as shown in Figs. 1, 2, 4 and 5.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a wall and a floor, refrigerating means adjacent the upper part of said wall, a vertical flue associated with said wall and adapted to conduct air and liquid from said means to the lower part of the car, a trough associated with said floor and arranged to receive liquid from said flue, a removable rack resting upon said floor to support a lading in spaced relation thereto and a foraminous sheathing provided with relatively small apertures arranged to substantially cover said trough, said sheathing being arranged to swing upwardly, said rack having a part arranged to overlie a part of said sheathing to hold the sheathing in its covering position.

2. In a refrigerator car having a lading compartment defined in part by a wall and a floor, refrigerating means adjacent the upper part of said wall, a vertical flue associated with said wall and adapted to conduct air and liquid from said means to the lower part of the car, a trough associated with said floor adjacent the lower end of said flue and arranged to receive liquid from said flue and a foraminous sheathing provided with relatively small apertures arranged to substantially cover said trough, said sheathing being formed to direct said air into the lading compartment.

3. In a refrigerator car having spaced apart walls, roof and floor which enclose a lading compartment, refrigerating means in the upper part of the car adjacent one of said walls, a trough associated with said floor, flue means associated with said last mentioned wall and arranged to conduct liquid from said refrigerating means to the lower part of the car, and a plate overlying said trough, said plate having a plurality of small apertures thereby permitting relatively small quantities of liquid from said flue means to filter

into said trough and at the same time preventing relatively large quantities of liquid from splashing out of said trough into said lading compartment during movements of the car.

4. In a refrigerator car having spaced apart walls, roof and floor which enclose a lading compartment, refrigerating means in the upper part of the car adjacent one of said walls, a trough associated with said floor, flue means associated with said last mentioned wall and arranged to conduct liquid from said refrigerating means to the lower part of the car, and an upwardly concave plate overlying said trough, said plate permitting relatively small quantities of liquid from said flue means to filter into said trough and at 15 the same time preventing relatively large quantities of liquid from splashing out of said trough into said lading compartment during movements of the car.

5. A structure as defined in claim 3 wherein said sheathing has its lowest part included between the edges thereof, said lowest part overlying said trough.

6. A structure as defined in claim 3 including spaced apart baffles depending from said sheathing to prevent surging of liquid in said trough.

7. In a refrigerator car having a wall and a floor, refrigerating means adjacent the upper part of the wall, a trough associated with said floor, flue means associated with said wall and arranged to conduct liquid from said refrigerating means to said trough, and a plate provided with a plurality of relatively small apertures arranged to cover said trough, said plate being concave upwardly with the lower part thereof overlying said trough.

EARL R. SWANSON.
